UNITED STATES PATENT OFFICE.

MAX JASPER, OF BERLIN, GERMANY.

SAFETY-CLOSURE FOR CONTAINERS OF INFLAMMABLE LIQUIDS.

1,105,276.

Specification of Letters Patent. Patented July 28, 1914.

Original application filed September 18, 1912, Serial No. 720,940. Divided and this application filed December 17, 1912. Serial No. 737,175.

To all whom it may concern:

Be it known that I, MAX JASPER, a citizen of Germany, residing at Berlin, Germany, have invented a new and Improved 5 Safety-Closure for Containers of Inflammable Liquids, of which the following is a specification.

This invention relates to a safety closure for bottles, jars, cans and similar containers 10 of inflammable liquids, the present application being a division of an application filed by me September 18th, 1912 under Serial No. 720,940.

The closure is adapted to be fitted into the 15 mouths of such containers as are provided with but a single ingress and egress opening, so that it permits the pouring in as well as the pouring out of the liquid. The construction should be such that the closure cannot 20 be readily removed by unauthorized persons. So also the closure should effectively prevent the flame from striking inward, for which purpose it should be made to effectively conduct the heat generated, which latter purpose is rendered more difficult by the 25 location of the closure within the mouth of the container.

In the accompanying drawing: Figure 1 is a side view partly in section of part of a 30 container embodying my invention; Fig. 2 a similar view of a modification, and Fig. 3 a similar view of a still further modification.

Referring more particularly to Fig. 1, the 35 neck 10 of a bottle, jar, can or other container for inflammable liquids is provided with a head 11. Within neck 10, there is housed a foraminated member 12, shown to be composed of a small meshed wire tube or elongated net open at the top. Means are 40 provided for firmly securing the tube 12 to head 11 and for abstracting the heat from tube 12. These means consist of an annular metal cap 13 secured to the upper end of tube 12 and extending from the interior of 45 the bottle head 11 around the outer face of the same. At its top, cap 13 is provided with an annular bead 14 that accommodates a packing ring 15 and also prevents the liq-

uid from splashing while being poured out. In order to secure the cap to the bottle, there 50 is provided a stopper 16 having a bail 17, on which turn a pair of arms 18, the bent ends of which enter a pair of diametrically opposed apertures 19 formed in the cap and bottle. The safety device can thus only be 55 detached by withdrawing arms 18 from apertures 19.

In Fig. 2, the cap 13 is secured to the bottle by turning its lower end or flange 20 inwardly to project beneath head 11. With 60 this construction, the device can only be removed by unbending flange 20.

In Fig. 3, cap 13 is provided with a concave peripheral bead 21 that enters a corresponding groove 22 of head 11, said groove 65 being preferably provided with a gasket 23. The lower end of cap 13 is turned outwardly to form an annular trough 24 adapted to collect drippings of the inflammable liquid. In this way, the burning liquid cannot reach 70 the hand of the operator, so that a resulting involuntary release of the bottle and a consequent explosion are avoided.

It is obvious that changes may be made in the construction of the safety device without departing from the spirit of my invention. 75

I claim:

1. A bottle adapted to contain inflammable liquids, provided with a heat conductive 80 cap that extends from the interior of the bottle head downwardly over the outer face thereof, to inclose said head, said cap constituting a stopper-seat, a stopper adapted to engage said seat, a heat conductive crib- 85 rate member that is attached to the cap and depends from the inner end thereof into the neck of the bottle, and means for irremovably securing the cap to the bottle head, whereby a withdrawal of the cribrate mem- 90 ber from the interior of the bottle is prevented in the closed as well as in the open position of the stopper.

2. A bottle adapted to contain an inflammable liquid combined with a heat conductive 95 cap that snugly embraces the exterior of

the bottle-head and extends downwardly into the interior of said head, a heat conductive cribleate member depending from the inner end of the cap into the bottle-neck, and means for irremovably securing the cap to the bottle-head whereby the cribleate member is likewise irremovably secured to said

head and a removal of the cap and cribleate member from the bottle without destroying cap-securing means is rendered impossible. 10

MAX JASPER.
